UNITED STATES PATENT OFFICE.

WILLIAM M. HUMBERT, OF MARSHFIELD, OREGON.

BATTERY-SEPARATOR-PLATE MACHINE.

Application filed December 22, 1923. Serial No. 682,313.

To all whom it may concern:

Be it known that I, WILLIAM M. HUMBERT, a citizen of the United States, residing at Marshfield, in the county of Coos and State of Oregon, have invented new and useful Improvements in Battery-Separator-Plate Machines, of which the following is a specification.

This invention relates to the wood working art, particularly to special work machines and has for its object the provision of a machine for cutting the wooden plates used as separators between the plates of a storage battery.

More specifically the object of the invention is to provide a machine for this purpose which will automatically act to cut a block of wood into a plurality of thin sheets which are plane on one side and grooved on the other side as the accepted formation in storage battery construction.

Another object is the provision of a machine of this character including a support carrying the block of wood and along which is slidable a frame carrying two knives, one for cutting the sheet and the other for grooving one side thereof, both knives accomplishing their cutting action almost simultaneously so that only a single operation is necessary.

An additional object is the provision of a machine of this character which will be simple and inexpensive in manufacture, easy to operate and control, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a side elevation of the machine,

Figure 2 is a top plan view thereof,

Figure 3 is a longitudinal section,

Figure 4 is a cross section taken in advance of the blades,

Figure 5 is a bottom plan view of the carriage,

Figure 6 is a perspective view of one of the cut sheets,

Figure 7 is a detail perspective view of the toothed blade,

Figures 8 and 9 are detail views.

Referring more particularly to the drawings the numeral 10 designates broadly a supporting frame or stand which is here shown as including bottom sills 11 from the forward and rear ends of which rise 60 preferably inclined and converging supports 12 and 13 respectively. Transverse bars 14 and 15 connect the rear uprights 13, and spaced parallel longitudinal channeled guides 16 connect the upper ends of the uprights 12 and 13. This exact frame construction might of course be varied, though what is shown is sufficient to carry out the purposes of the invention.

On the guides 16 are bearings 17 for a 70 transversely arranged shaft 18 equipped at one end with a fly wheel 19 and at its other end with a drive pulley 20 to which power may be applied for rotating the shaft. Intermediate its ends the shaft is formed with 75 a crank portion 21 carrying a roller 22.

Slidable within and between the guides 16 is an elongated frame including side members 23 connected at their ends by transverse members 24 and 25. At one end, namely the 80 upper end, this frame has pivotally connected therewith a rod 26 which has its free end slidable through a bearing 27 on the cross bar 14. Intermediate its ends the rod 26 is formed with a laterally elongated 85 loop 28 within which is engaged the roller 22 so that when the shaft 18 is rotated, the movable frame will be reciprocated along the guides 16.

Secured to the lower end of the guides 90 is a stop 29 adapted to engage and hold the block of wood 30 to be cut into separator plates or sheets.

The movable frame or carriage includes an elongated plate 31 which is secured to 95 the sides 23 and which has its upper edge cut away diagonally as indicated at 32. At a point spaced from this diagonal end the plate is formed with an elongated diagonal slot 33.

Secured upon the sides 23 of the movable frame or carriage and located above the plane of the plate 31 is a diagonally arranged blade 34 which has its cutting edge 35 registering with the diagonal edge 32 of the plate. This blade is spaced from the plane of the plate 31 a distance equal to the thickness of the separator plates desired, and it is preferable to provide the screw adjustment for varying the position of this blade so that

separators of different thicknesses may be cut.

Extending transversely of the frame or carriage and in a diagonal direction is a bar 37 located at the diagonal edge 32 of the plate 31 and carrying a blade 38 formed with a plurality of teeth 39 which project upwardly through the slot 33 for grooving the underside of the separator plate as it is cut. The blade 38 is formed with slots 40 through which pass securing screws 41, this arrangement permitting adjustment of the blade for regulating the degree of projection of the teeth 39 and consequently the depth of the grooves in the separator plate.

In the operation it will be seen that as the shaft 18 is rotated, the movable frame or carriage will be reciprocated along the guides 16, and at every forward movement the teeth 39 will dig into and groove the underside of the block 30. After the teeth have traveled part of their course, the blade 34 will contact with the forward edge of the block and slice off the bottom thereof so as to form the thin battery plate separator known to commerce. If preferred, I may provide small blades 42 which project upwardly from the plate 31 and which will operate to cut the operator plate to the desired width.

From the foregoing description and a study of the drawings it will be apparent that I have thus provided a very simply constructed and consequently inexpensive machine which will operate conveniently and rapidly to cut a block of wood into a plurality of perfectly formed and identically similar separator plates. It is to be observed that ample provision is made for varying the depth of the grooves in one face of the separator and for varying the thickness of the separator cut so that all variations necessary may be made.

While I have shown and described the preferred embodiment of my invention it is of course to be understood that I reserve the right to make such changes in the form, construction and arrangement of parts as will not depart from the spirit of the invention or the scope of the subjoined claims.

Having thus described my invention I claim:

1. In a machine of the character described, a supporting frame including an inclined guide way, an abutment member located transversely of and mounted upon the guide way and adapted to support a block of wood, a frame longitudinally movably mounted within the guide way, means for reciprocating the frame, a plate mounted on and forming part of the frame, said plate being formed with a diagonal slot, a diagonally arranged blade parallel with and mounted above the plate adapted to cut through a block of wood for forming a slice at the lower side thereof, and a second blade

mounted within said slot and having a toothed edge projecting thereabove for grooving the under side of the slice.

2. In a machine of the class described, a supporting frame including an inclined guide way, an abutment member located transversely of and mounted upon the guide way and adapted to support a block of wood, a frame longitudinally movably mounted within the guide way, means for reciprocating the frame, a plate mounted on and forming part of the frame, said plate being formed with a diagonal slot, a diagonally arranged blade parallel with and mounted above the plate adapted to cut through a block of wood for forming a slice at the lower side thereof, and a second blade mounted within said slot and having a toothed edge projecting thereabove for grooving the under side of the slice, and means connected with the first named blade for varying the position thereof to regulate the thickness of the slice cut thereby.

3. In a machine of the character described, a supporting frame including an inclined guide way, an abutment member located transversely of and mounted upon the guide way and adapted to support a block of wood, a frame longitudinally movably mounted within the guide way, means for reciprocating the frame, a plate mounted on and forming part of the frame, said plate being formed with a diagonal slot, a diagonally arranged blade parallel with and mounted above the plate adapted to cut through a block of wood for forming a slice at the lower side thereof, and a second blade mounted within said slot and having a toothed edge projecting thereabove for grooving the under side of the slice, said slot being inclined with respect to the longitudinal axis of the frame, and the second named blade being formed with elongated slots through which pass securing members whereby the degree of projection on the toothed edge beyond said plate may be varied for regulating the depth of the grooves.

4. In a machine of the character described, a stationary supporting frame including an inclined guide way, an abutment member extending transversely of the guide way and adapted to support a block of wood, a frame mounted for longitudinal movement within the guide way, a pair of blades carried by said frame, one blade being adapted to slice a block of wood and the other being adapted to score or groove the under side thereof, a rod slidably mounted longitudinally of the guide way and formed with a transversely arranged open loop, a pivotal connection between said loop and said movable frame, a shaft journaled transversely of the guide way and having a crank portion engaged within said loop.

5. In a machine of the character described, a supporting structure adapted to hold a block of wood to be cut, a frame slideable along said supporting structure and including a plate having a slot therein, a blade carried by said frame and spaced above said plate, and a blade mounted beneath the underside of said plate and having a toothed edge projecting through the slot therein for grooving the underside of the block of wood, said second named blade being carried by a transverse bar and formed with slots, and screws passing through said slots whereby to permit adjustment of the second named blade to vary the degree of projection of the teeth beyond the plate. 20
10 grooving the underside of the block of wood, and adjusting screws for maintaining said first named blade in position and permitting adjustment thereof toward or from the plane of said plate.
- 15 6. In a machine of the character described, a supporting structure adapted to hold a block of wood to be cut, a frame slideable along said supporting structure and including a plate having a slot therein, a blade carried by said frame and spaced above said plate, and a blade mounted beneath the underside of said plate and having a toothed edge projecting through the slot therein for grooving the underside of the block of wood, said second named blade being carried by a transverse bar and formed with slots, and screws passing through said slots whereby to permit adjustment of the second named blade to vary the degree of projection of the teeth beyond the plate. 25
30

In testimony whereof I affix my signature.
WILLIAM M. HUMBERT.
